UNITED STATES PATENT OFFICE.

HERMANN MICHEL, OF HOLSTEIN, GERMANY.

REVERSING GEAR FOR TWO-STROKE CYCLE INTERNAL-COMBUSTION ENGINES.

Application filed October 26, 1922. Serial No. 596,974.

To all whom it may concern:

Be it known that I, HERMANN MICHEL, a citizen of Germany, and a resident of Voorde i. Holstein, Germany, have invented 5 certain new and useful Improvements in Reversing Gears for Two-Stroke Cycle Internal-Combustion Engines, of which the following is a specification.

My invention relates to improvements in 10 reversing gears for two-stroke cycle internal combustion engines. In two-stroke cycle internal combustion engines the reversing mechanism comprises a cam shaft carrying cams for forward and rearward operation 15 and adapted to be shifted for bringing either one of said cams into operative position. In other constructions the cam shaft is provided only with one set of cams, and it is adapted to be turned at a suitable angle, which for example in engines of the 20 Diesel type is about 30°. The construction of the cam shaft and the mechanism for setting the same angularly is complicated, so much the more as it must be such as to permit 25 setting while the engine is running. In addition the cams controlling the fuel supply and the starting mechanism must be turned at different angles.

In other constructions of two-stroke 30 cycle combustion engines the cam disk is equipped with a single cam controlling the two-stroke cycle and cooperating with a rockable valve lever adapted to be shifted longitudinally in a direction opposite to 35 that of the cam for reversing the engine. The angle through which the lever is shifted relatively to the cam is about 30°. Therefore, the direction of the force exerted by the cam on the lever acts at a large angle 40 to the force of the spring of the valve acting tangentially of the fulcrum of the valve lever on the cam disk. This results in a high reaction on the valve gear and a heavy pressure between the cam and the lever.

45 The object of the improvements is to provide a construction in which the said reaction on the valve gear and the wear of the engaging parts of the cam and the valve lever are reduced, and with this object in 50 view my invention consists in providing the cam disk with a plurality of cams for a plurality of successive two-stroke periods, and reducing the number of revolutions of the cam disk at the ratio of the number of 55 the cams. Thereby the angle between the

end positions of the valve lever or the anti-friction roller carried thereby relatively to the cam disk is reduced at the ratio of the numbers of the cams, said angle being reduced for example in case of three cams 60 from 30° to 10°. In this case the direction of the reaction exerted by the cam disk and the direction of the force caused by the valve spring and acting tangentially of the fulcrum of the valve lever are at an angle 65 of 5°.

For the purpose of explaining the invention several examples embodying the same have been shown in the accompanying drawing, in which the same reference characters 70 have been used in all the views to indicate corresponding parts. In said drawing,

Fig. 1, is a diagrammatical view of a system now in use and comprising a single cam on the steering shaft, 75

Fig. 2, is an elevation largely diagrammatic and partly in section showing my improved reversing mechanism,

Fig. 3, is a sectional elevation showing a modification, 80

Fig. 4, is a plan view of Fig. 3,

Fig. 5, is an elevation showing another modification, and

Fig. 6, is a section taken on the line 6—6 of Fig. 5 and looking in the direction of the 85 arrows.

In the construction shown in Fig. 1 illustrating a part of the steering mechanism of an engine of the Diesel type a single steering cam *c* is provided on a disk *b* having 90 rotary movement on a shaft *a*. The cam cooperates with a lever *f* carrying a roller *d* and adapted to operate the fuel admission valve (not shown). For reversing the engine the lever *f* is shifted in longitudinal 95 direction a distance corresponding to an angle *α* of about 30°. If the position of the axis of the roller *d* in case of forward movement is I and for backward movement II, the said angle *α* is disposed between the lines 100 I—*a*— and *a*—II.

In any position of the roller the direction of the radial reaction of the cam disk forms an angle of 15° to the force caused by the valve spring and acting transversely 105 of the fulcrum of the valve lever, so that a strong reaction is caused.

As appears from Fig. 2, in my improved construction the cam disk 2 rotatable about the axis 1 carries three cams displaced with 110

relation to each other at angles of 120° . In order to have cams 4 of the same form as that shown in Fig. 1, in engines of similar power the diameter of the disk 2 is larger than that of the disk 6. The cam disk 2 operates with an arm 7 of a valve lever having its fulcrum at 8 and carrying an anti-friction roller 6. The arm 9 of the valve lever bears on the stem 10 of a valve 11 actuated upon by a spring 12 tending to force the same on its seat. The lever 7, 9 is adapted to be shifted longitudinally of its length by suitable means. To show what may be done the lever is mounted on a rocker 13 adapted to be rocked to the right or left in Fig. 2 for reversing the engine.

In the position shown in Fig. 2 in full lines the valve gear has been set for forward operation of the engine corresponding to the position I of the roller 6. The cam disk 2 rotates in the direction of the arrow shown in full lines. For reversing the engine the lever 7, 9 is shifted in a direction opposite to the rotation of the cams 4 and into the position II shown in dotted lines. The angle I—II which corresponds to the displacement of the lever 7, 9 is about 10° . Therefore, in both cases the position of the roller 6 is such that the direction of the radial reaction of the cam disk 2 and the direction of the force acting tangentially of the fulcrum of the valve lever 7, 9 and exerted by the valve spring 12 are at an angle of 5° , so that the reaction is reduced to a minimum.

In the modification shown in Figs. 3 and 4 the cam disk 2' is disposed perpendicularly to the valve lever 7', 9' acting on the valve 11', which construction is necessary in some cases in view of other parts of the engine. In such cases the lever 7', 9' is rockingly mounted on an arm 14 mounted for rocking about the vertical axis of the valve 11'. As shown the arm 14 is provided with a hub 15 mounted on the valve casing 16. At its free end the arm 14 is formed with an eye 17 providing a bearing for a vertical pivot bolt 18 adapted to be rocked within said bearing and to be shifted therein in axial direction. At its bottom end the said pivot bolt carries the roller 6', and at its top end an axial pin 19 engaging the free end of the arm 7'. On the eye 17 an arm 20 is rockingly mounted, and the pivot bolt 18 is non-rotatable but longitudinally shiftable within the hub of the said arm, for which purpose it is connected therewith for example by a feather 20'. The arm 20 is connected by a link 21 parallel to the arm 7', 9' with a relatively fixed part of the frame 22 of the engine, the frame 22, the valve lever 7', 9', the arm 20, and the link 21 providing a parallel guide for holding the roller 6' in a plane parallel to the cam disk when rocking the arm 14 for reversing the

engine. Suitable means are provided for rocking the arm 14 and locking the same in either one of its positions. Such means will readily suggest themselves to those skilled in the art and have therefore not been shown in the drawing.

In Figs. 5 and 6 I have shown a modification in which the cam disk 2'' is likewise perpendicular to the valve lever 7'', 9'' acting on the valve 11''. The roller 6'' is mounted on a lever 23 disposed in a plane passing through the cam disk 2'' and jointed to a rocker 24 adapted to be rocked for shifting the roller relatively to the cams 4'' in the manner described with reference to Figs. 1 to 4. The top face of the lever 23 is in engagement with the valve lever 7'', 9'' having its fulcrum at 8''. When reversing the engine the lever 7'', 9'' is rocked about its fulcrum 8'', but otherwise its position is not varied, the lever 23 being free to be moved independently of the lever 7'', 9'' and transversely thereof. The lever 23 can be comparatively light and weak, because it has only the function to transmit the pressure from the roller 6'' to the lever 7'', 9''.

While in describing the invention reference has been made to particular examples embodying the same I wish it to be understood that my invention is not limited to the constructions shown in the drawing, and that various changes may be made in the general arrangement of the apparatus and the construction of its parts without departing from the invention.

I claim:

1. In a valve gear for two-stroke cycle internal combustion engines, a valve, a cam disk carrying a plurality of cams for a plurality of cycles, and a valve operating lever adapted to be operated on one side of its fulcrum by said cams and the other side thereof being adapted to operate said valve and means for shifting said lever circumferentially of said disk.

2. In a valve gear for two-stroke cycle internal combustion engines, a valve, an arm movable about the axis of said valve, a valve lever fulcrumed on said arm, and a cam disk carrying a plurality of cams for a plurality of cycles and disposed with its plane substantially perpendicular to said lever, said valve lever being in position for cooperation with said cams and valve.

3. In a valve gear for two-stroke cycle internal combustion engines, the combination with the valve, of an arm movable about the axis of said valve, a valve lever, a cam disk carrying a plurality of cams for a plurality of cycles and disposed with its plane substantially perpendicular to said lever, a pivot bolt rotatable and longitudinally shiftable in said arm and engaging said lever, a roller carried by said pivot bolt and in position for cooperation with said cams,

- and a parallel guide connected with said pivot bolt and adapted to hold said roller within the plane of the cam disk.
4. In a valve gear for two-stroke cycle internal combustion engines, a valve, a cam disc carrying a plurality of cams for a plurality of cycles, an arm movable about the axis of said valve and a lever carried by said arm and adapted to operate said valve and a pivot bolt carried by said lever adapted to contact with said cams.
5. In a valve gear for two-stroke cycle internal combustion engines, a valve, a cam disc carrying a plurality of cams for a plurality of cycles, an arm movable about the axis of said valve and a lever carried by said arm and adapted to operate said valve, and in position for engagement with said cams.
5. In a valve gear for two-stroke cycle internal combustion engines, a valve, a cam disc carrying a plurality of cams for a plurality of cycles, an arm movable about the axis of said valve, a lever carried by said arm and adapted to operate said valve and a pivot bolt carried by said lever adapted to contact with said cams.

In testimony whereof I hereunto affix my signature.

HERMANN MICHEL. [l.s.]
